C. W. WYMAN

INTERLOCKING MECHANISM

Filed March 22, 1924

Charles W. Wyman, Inventor:
by Oracle L. [unclear].

Attorney.

UNITED STATES PATENT OFFICE.

CHARLES W. WYMAN, OF CLAREMONT, NEW HAMPSHIRE, ASSIGNOR TO SULLIVAN MACHINERY COMPANY, A CORPORATION OF MASSACHUSETTS.

INTERLOCKING MECHANISM.

Application filed March 22, 1924. Serial No. 701,225.

My invention relates to interlocking mechanism.

An object of my invention is the provision of an improved interlocking mechanism especially adapted to control the movements of an electric switch and a cooperating connector plug whereby each is controlled in certain positions of the other. More particularly, my invention has for its object the provision of an improved interlock controlling mechanism controlling a switch and a connector plug especially adapted to use in connection with mining machines intended for use in gas laden atmospheres and functioning to prevent the ignition of the gas during movement of the switch or the connector plug, this being accomplished by preventing the making or breaking of any circuits by movements of the connector plug while the switch is closed, or the movement of the switch to closed position when the connector plug is only partially inserted and so liable to withdrawal with resultant breaking of a circuit.

It will be understood that my invention may be embodied in various forms, but I have shown in the accompanying drawings, for purposes of illustration, one of the forms which it may assume in practice, illustrating this form as applied to a mining machine.

In these drawings,—

Fig. 1 is a side elevation of a mining machine equipped with the illustrative embodiment of my improvement.

Fig. 2 is an enlarged detail sectional view on the broken line 2—2 of Fig. 3.

Fig. 3 is a sectional view on the line 3—3 of Fig. 2.

Fig. 4 is a detail sectional view on the section line 4—4 of Fig. 2.

In the illustrative construction I have disclosed a mining machine M of standard form and supplied with three-phase alternating current through a cable 1 terminating in a plug 2 which provides several different contacts numbered 3, 4, 5 and 6, of which the first three are connected to power wires within the cable 2 and the fourth to a ground wire therein. The element 6 is larger than the others to compel proper insertion of the plug. Current flow from the several power wires to the usual motor on the machine is controlled by a suitable main line switch, herein

distinct from the controller which is not shown, this switch comprising a plurality, herein three, movable switch contacts, herein in the form of knife blades 7, 8, 9 each of which is pivotally connected, as shown at 10 in the case of the blade 7, with a stationary contact and each of which is pivotally movable into engagement with a clip-like contact, indicated at 11 in the case of the blade 7. It will be understood that the connector plug 2, not all of whose details are shown as they do not, other than as illustrated, enter into the invention, is adapted to engage, through its contacts 3, 4, 5 and 6 with suitable stationary sockets, which are arranged to receive these elements when the plug is in position.

It will be observed that the several blades 7, 8, 9 are held to each other and moved together by means of a bar 13 which may be in the form of a rod running inside an insulating tube and having a series of larger tubes surrounding the first mentioned tube for the purpose of spacing the blades from each other and from the holding means at the ends of the member 13. Pivotally connected to the bar 13 at points adjacent the ends of the latter but spaced just inside the blades 7 and 9 are links 14 and 15 which are pivoted at their opposite ends as indicated at 16 and 17 to arms 18 and 19 carried on a sleeve 20 which is secured in non-rotative relation to a shaft 21. This shaft is the operating shaft for the switch and is provided with a handle 22 secured to one end thereof outside a casing 23 which houses the switch mechanism and the socket for the plug. It will be noted from Figs. 2 and 4 that the shaft 21 is cut away at a point between its ends and opposite a recess 24 into which the plug is intended to be forced, so that the cylindrical exterior surface of the plug may in a particular position of the shaft 21 be free to move longitudinally. The peripheral surface of the plug is also cut away as indicated at 26 to permit in the full seated position of the plug, the rotation of the shaft 21, it being evident from Fig. 4 that when the shaft 21 is rotated to cause closing of the switch, an uncut portion of its periphery enters the notch 26 in the plug and so prevents possible removal of the plug and likewise would prevent insertion of the latter if it were out. It is to be noted that leads from the fixed contacts of the connector lead to and

are secured as by suitable nuts or binding posts 27 to the contacts 11 while other leads lead off to the motor from similar nuts 28 associated with the stationary pivoted contacts 10. A series of insulating plates 30, 31, 32 and 33 are held together by suitable rods 34 and 35 and these are so arranged that each blade and the contact with which it is adapted to cooperate is positioned between a pair of plates. The set of plates may be held in position by spring clips 36 and the seating of certain plates in sockets therefor, which permits easy removal, the clips cooperating with an insulating plate 37 on which the switch parts are mounted.

From what has been said the advantages of this construction need no extended amplification. However, it may be said that when the plug is in position and the switch is closed, it is positively held against jarring opening due to the cooperation of the links 15 and 19 and 14 and 18 which form in effect a toggle mechanism. In the event that any effort is made to withdraw the plug when the circuit is closed, this will of course be frustrated by the impossibility of withdrawing the plug due to the interlock between the socket 26 and the shaft 21, and it is obviously impossible to close the switch with the plug partially in place, where it is apt to be withdrawn or knocked out, due to the fact that the shaft 21 can only be rotated when it is opposite the groove 26 and this does not come opposite the shaft until the plug is fully home.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

45 1. In an interlocking mechanism, a pivoted switch, a connector, an actuating mechanism for said switch including a shaft eccentric to the axis of pivoting of said switch and extending to opposite sides of said connector, and interlocking connections on said shaft and connector.

50 2. In an interlocking mechanism, a pivoted switch, a connector, an actuating mechanism for said switch including a shaft eccentric to the axis of pivoting of said switch, and interlocking connections between said shaft and connector comprising grooves in each of the same.

55 3. In an interlocking mechanism, a pivoted switch, a connector, an actuating mechanism for said switch including a shaft eccentric to the axis of pivoting of said switch, and interlocking connections between said shaft and connector including grooves in each of the same for preventing insertion of the con-

nector when the switch is closed, or closing of the switch when the connector is partially inserted.

4. In an interlocking mechanism, a pivoted switch blade, a rock shaft, a toggle connection between said blade and shaft, a connector, and interlocking connections between said shaft and connector. 70

5. In an interlocking mechanism, a plurality of parallel pivoted switch blades, means connecting them for simultaneous pivotal movement, a shaft parallel to the axis of such pivotal movement, toggle connections between said shaft and means, a connector, and interlocking connections between said shaft and connector. 75

6. In an interlocking mechanism, a plurality of parallel pivoted switch blades, means connecting them for simultaneous pivotal movement, a shaft parallel to the axis of such pivotal movement, toggle connections between said shaft and means, a connector, a socket therefor, the direction of insertion and removal of said connector being parallel to the plane of pivotal movement of said switch blades, and interlocking connections between said shaft and connector. 80

7. In a mechanism of the class described, a plurality of switch elements, actuating means therefor including toggle mechanism comprising elements adapted to be straightened into alignment on closure of said switch, a connector plug, and means for actuating said first mentioned actuating means interlocking with said plug. 95

8. In a mining machine, a frame carrying a casing, a main line switch in said casing having an operating shaft, a socket in said casing to receive a connector plug, ground and power wires terminating in a connector plug, and direct interlocking connections between said shaft and plug. 100

9. In an interlocking mechanism, a switch, a connector comprising a member supporting a plurality of contact elements adapted to make circuits on contact with other elements with respect to which they are relatively movable, and a switch operating shaft, said member having a peripheral recess interlocking with said shaft to lock said connector in 110 circuit making position while said switch is closed. 115

10. In an interlocking mechanism, a switch, a connector comprising a member supporting a plurality of contact elements adapted to make circuits on contact with other elements with respect to which they are relatively movable, a switch operating shaft, said shaft having a peripheral recess filled by said member when the latter is adjacent to but out of circuit making position whereby said switch is held in open position. 120

11. In an interlocking mechanism, a switch, a connector comprising a member supporting a plurality of contact elements adapted to 125

make circuits on contact with other elements with respect to which they are relatively movable, a switch operating shaft, and means including peripheral recesses in said member 5 and shaft for locking said connector in circuit making position or preventing its insertion while said switch is closed and for precluding closure of said switch when said member is adjacent to but out of circuit making position.

12. In combination, a plurality of knife blade switches having their movable elements pivotable about alined axes, a connector plug socket intersected by the line of said axes at a 15 point outside the planes of movement of said several movable elements, an operating shaft for said switches extending parallel to but offset from such line, and operative connections between said shaft and the movable elements of said switches, said shaft having a 20 portion extending in one position thereof into the bore of said socket and adapted to interlock with a plug receivable in the socket.

13. In combination, a plurality of knife blade switches having their movable elements 25 pivotable about alined axes, a connector plug socket intersected by the line of said axes at a point outside the planes of movement of said several movable elements, an operating shaft 30 for said switches extending parallel to but offset from such line, and operative connections between said shaft and the movable elements of said switches, said shaft having a portion extending in one position thereof into 35 the bore of said socket and adapted to interlock with a plug receivable in the socket and being cut away peripherally to permit locking by a plug in another position.

14. In combination, a plurality of knife blade switches having their movable elements 40 pivotable about alined axes, a connector plug socket intersected by the line of said axes at a point outside the planes of movement of said several movable elements and arranged with 45 its axis parallel to the planes of movement of the movable elements of said switches, an op-

erating shaft for said switches extending parallel to but offset from such line, and operative connections between said shaft and the movable elements of said switches, said shaft 50 having a portion extending in one position thereof into the bore of said socket and adapted to interlock with a plug receivable in the socket.

15. In combination, a plurality of knife 55 blade switches having their movable elements pivotable about alined axes, a connector plug socket intersected by the line of said axes at a point outside the planes of movement of said several movable elements and arranged with 60 its axis parallel to the movable elements of said switches when the latter are in closed position, an operating shaft for said switches extending parallel to but offset from such line, and operative connections between said 65 shaft and the movable elements of said switches, said shaft having a portion extending in one position thereof into the bore of said socket and adapted to interlock with a plug receivable in the socket. 70

16. In combination, a plurality of knife blade switches having their movable elements 75 pivotable about alined axes, a connector plug socket intersected by the line of said axes at a point outside the planes of movement of said several movable elements and arranged with 80 its axis parallel to the movable elements of said switches when the latter are in closed position, an operating shaft for said switches extending parallel to but offset from such line, and operative connections between said shaft 85 and the movable elements of said switches, said shaft having a portion extending in one position thereof into the bore of said socket and adapted to interlock with a plug receivable in the socket and being cut away peripherally to permit locking by a plug in another position.

In testimony whereof I affix my signature.

CHARLES W. WYMAN.
